ATTORNEYS.

UNITED STATES PATENT OFFICE

HARRY TRACY NELSON, OF DALLAS, TEXAS

HELICOPTER FLYING TOY

Application filed December 26, 1929. Serial No. 416,540.

The invention relates to new and useful improvements in helicopters or flying toys.

The object of the invention is to provide a helicopter or flying toy which may be used as a toy or for any other purpose for which it is suitable.

One object of the invention is to provide a helicopter with propellers revolving in opposite directions cooperating to propel the 10 device in the same direction and with a parachute attached to the lower end of the frame so that when the propellers cease to rotate and the helicopter begins to fall the parachute will be opened, thereby bringing the 15 helicopter safely and comparatively slowly to the ground, such an operation producing either a pleasing or useful effect, or both.

Another object of the invention is to provide a helicopter with a parachute attached 20 to the lower end, preferably by means of a swivel connection, so that the parachute is not rotated by the revolving motion of the helicopter and is free to hang dormant so that its cords will not become twisted while 25 the helicopter is ascending; together with means for holding the parachute closed during the ascent and automatically releasing the parachute to open at the beginning of the descent.

30 A further object of the invention is to provide a helicopter with a parachute attached to the lower end which by its trailing effect and resistance through the air provides supplemental means of assisting the helicopter 35 to continue in a vertical direction, thereby helping the toy to reach its maximum height.

A further object of the invention is to provide a flying toy of simple and light construction with demountable propellers and easily 40 replaced rubber bands so that it may be quickly and easily mounted or demounted and packed in a small container.

The invention may be more readily understood from a reading of the following specifications and by reference to the accompanying drawings, in which an example of the invention is shown and wherein:

Fig. 1 is a view of the flying toy which 50 is constructed in accordance with the inven-

tion and illustrates how it appears while ascending.

In the drawings the numeral 10 designates the frame which may be made of wood or wire to which is fastened the lower propeller, 34 55 by means of small bolts, 17 and 18.

At the upper end, propeller 12 is connected, the hook 14 passing through the hole at 19 and washer 15 is provided as a bearing. The propeller arms are bent as shown at 32 and 33 and the propeller blades made of paper or thin aluminum. At the lower end of the frame is hook 16. Between hooks 14 and 16 are connected several rubber bands which when wound up and released cause the propellers to revolve in opposite direction, 60 co-operating in lift.

Bolt 20 fastens hook 16 and also holds rigidly the element 21 of the swivel connection which is provided with eyelets 24 and 25 70 for bearings of the other element 22 of the swivel, which also extends downward and forms loop 26 to which is fastened the cords 30 of parachute 29. Arm 27 is also provided and extends outward from the axis of rotation of the swivel, being slightly curved upward near the end and which supports the upper end of the parachute by means of ring 28 during the ascent of the toy.

When the toy is wound up, launched and has reached its maximum height, it turns over, the upper part being heavier and the parachute acts as a tail and hangs dormant while ascending. The instant the toy starts to turn over, arm 27 swings inward and as the 80 toy starts downward the ring 28 slides off arm 27 and the parachute opens. The toy then descends gracefully in the parachute, thus producing a useful and attractive device.

Since the element 21 of the swivel is held rigidly and element 22 is free to turn relative to 21, arm 27 will always swing around on the inward side when the toy begins to turn over, regardless of the direction it happens to fall, and thus release the parachute at the proper 90 time.

Various changes in the size and shape of the different parts, as well as modifications and alterations may be made within the scope of the appended claims.

What I claim is:—

1. A flying toy with a parachute attached to the lower end of the frame by means including a swivel connection having a vertical axis, one element of the swivel being rigidly attached to the frame of the toy, the other element of the swivel having the cords of the parachute fastened to it and having a portion extending for supporting the top of the parachute.
- 5 2. A flying toy with a parachute attached to the lower end of the frame by means including a swivel connection having a vertical axis, one element of the swivel being rigidly attached to the frame of the toy, the other element of the swivel having the cords of the parachute fastened to it and supporting the top of the parachute by means of an arm extending outward from the axis of the lower element of the swivel.
- 10 3. A flying toy with a parachute attached to the lower end of the frame by means including a swivel connection having a vertical axis, one element of the swivel being rigidly attached to the frame of the toy, the other element of the swivel having the cords of the parachute fastened to it and supporting the top of the parachute by means of an arm extending outward from the axis of the lower element of the swivel, means on top of the parachute for being supported by the arm.
- 15 4. A toy helicopter having a frame, two propellers arranged to revolve in opposite directions with respect to each other, a power unit, a parachute attached to the lower end of the frame by means including a swivel connection, the swivel having a vertical axis, one element of the swivel attached rigidly to the frame, the other element of the swivel, having the cords of the parachute fastened to it, same element of swivel also having a hook portion extending for supporting the top of the parachute, means on top of the parachute for being supported by same element of swivel.
- 20 5. A toy helicopter having a frame, two propellers arranged to revolve in opposite directions, with respect to each other, a power unit, a parachute attached to the lower end of the frame by means including a swivel connection, the swivel having a vertical axis, one element of the swivel attached rigidly to the frame, the other element of the swivel having the cords of the parachute fastened to it, same element of swivel also having a hook portion extending for supporting the top of the parachute, by means of an arm extending outward from the axis of the lower element of the swivel, means on top of the parachute for being supported by same element of swivel.
